UNITED STATES PATENT OFFICE.

CHARLES ROZELL, OF HUTCHINSON, KANSAS.

DESIGN FOR A BILLET-LOOP.

SPECIFICATION forming part of Design No. 28,063, dated December 21, 1897.

Application filed November 11, 1897. Serial No. 658,214. Term of patent 14 years.

To all whom it may concern:

Be it known that I, CHARLES ROZELL, a citizen of the United States, residing at Hutchinson, in the county of Reno and State of Kansas, have invented a new and original Design for a Billet-Loop, of which the following is a specification.

This invention relates to a new and original design for a billet-loop; and it has for its object to provide a design of this character that shall be both useful and ornamental.

The leading feature of the design resides in an approximately rectangular frame having a flat intermediate cross-bar connecting the side pieces thereof between their ends, said side pieces of the frame having their portions at one side of the flat cross-bar disposed at substantially right angles to the latter, and their opposite portions disposed at an obtuse angle to said flat cross-bar. The approximately rectangular frame includes the opposite parallel side pieces and cross-bars connecting the extremities of these side pieces, and a minor feature of the design may be stated to be in providing one of the end cross-bars of the frame between its ends with a right-angularly-disposed stud projection.

In the drawings, Figure 1 is a perspective view of a billet-loop embodying the herein-described design. Fig. 2 is a longitudinal sectional view thereof. Fig. 3 is a plan view of the same.

Referring to the accompanying drawings, 1 designates an approximately rectangular frame, essentially comprising the parallel side pieces 2, and end cross-bars 3, connecting the terminals of these side pieces and lying in parallel planes. Intermediate of the end cross-bars 3 the approximately rectangular frame 1 is provided with a wide flat cross-bar 4, which connects the side pieces 2 at an intermediate point, and is provided in one edge with an approximately U-shaped opening 4a.

At one side of the intermediate flat cross-bar 4 the side pieces 2 are disposed at substantially right angles to the same, while the portions of the side pieces at the other or opposite side of said cross-bar are disposed at an obtuse angle to the latter. The end cross-bar 3, connecting the obtuse-angled portions of the side pieces 2, is provided at its inner side and centrally between the ends thereof with a right-angularly-disposed stud projection 7, which completes the design.

What I claim is—

The design for a billet-loop herein shown and described.

In testimony that I claim the foregoing as my own I have hereto affixed my signature in the presence of two witnesses.

CHARLES ROZELL.
